Elsie J. Das, Honolulu, Territory of Hawaii, assignor to Watumull Brothers, a firm composed of Jhamondus Watumull, Gobindram J. Watumull, and Ramchand Watumull, and doing business as East India Store, Honolulu, Territory of Hawaii

Application January 4, 1937, Serial No. 66,878

Term of patent 3½ years

To all whom it may concern:

Be it known that I, Elsie J. Das, a citizen of the United States, residing at Honolulu, in the county of Honolulu, Territory of Hawaii, have invented a new, original, and ornamental Design for Textile Fabrics, of which the following is a specification, reference being had to the accompanying drawing, forming part thereof.

In the accompanying drawing:—

The figure is a face view of a textile fabric, showing my new design.

The unit of the design is indicated by the area bounded by the dot and dash lines.

I claim:

The ornamental design for a textile fabric, substantially as shown and described.

ELsie J. Das.
